(57) **CLAIM**

The ornamental design for a transformer, as shown and described.

DESCRIPTION

FIG. 1 is a front perspective view of a transformer showing my new design.

FIG. 2 is a front view of the transformer.

FIG. 3 is a rear view of the transformer.

FIG. 4 is a left side view of the transformer.

FIG. 5 is a right side view of the transformer.

FIG. 6 is a top view of the transformer.

FIG. 7 is a bottom view of the transformer; and,

FIG. 8 is a rear perspective view of the transformer.

Any shading and cross-hatching are not features of the design but are utilized to illustrate the surface contours of the transformer design in the drawings.
